COLLECTION DEVICE

William F. Kruschwitz, Methuen, Mass.

Application March 23, 1953, Serial No. 344,010

4 Claims. (Cl. 109—52)

This invention relates to a collection device or door collection device and is somewhat similar to Kruschwitz et al., "Door Collection Receptacle" of February 17, 1942, No. 2,273,580, but it is intended for a somewhat broader and more extensive use than merely as a depository for money to be taken by a driver for a laundry, drycleaner, or milk route, etc., whereby the customer could leave a definite amount of money in a locked box which the driver could unlock with a particular key.

This collection device includes one or more attaching or holding plates, one to be permanently attached to the frame of a house, preferably the door frame and near an outside door and the other holding plate to be attached to a wall, shelf etc. in the kitchen or somewhere in the house convenient for the householder.

The collection device also includes a receptacle comprising an outer tubular supporting member which is attachable or detachable to a base plate by rotation relative thereto and which completely covers the means for securing the base plate to a wall. It also includes an inner tubular locking member which telescopes inside such outer supporting member and is provided with means whereby when the outer member is put in place on a base plate and the inner member is put inside it, the outer and the inner members are locked against rotation on the base plate. The inner member is prevented from withdrawal from the outer member by means of a lock provided with two keys, one of which is kept by the householder and the other one of which is kept by the driver.

Where there are more than one collecting and delivering business concerns, such as the milkman, the laundryman, dry cleaner, etc. a separate and different collection receptacle with different keys is necessary for each concern, but only one base plate permanently attached by screws or otherwise, to the door frame or other convenient plate is necessary. However, an extra base plate is preferably provided with each device to be attached permanently in a convenient place inside the home such as a kitchen cabinet, so that such receptacle when not in use, can be put and out of the way on its own base plate.

This means that there needs to be only one plate outside the house on the door frame and there may be several receptacles, each with a separate key for use with a particular laundry, milkman, etc., or of course, there may be several such plates on the outside frame, one for each concern.

Each one of these collection devices is intended to be utilized by the householder by putting the key to the outside door and a certain amount of money in the receptacle and, if necessary, leaving the laundry inside the house near the door. The driver, therefore, can unlock the receptacle, remove the inner locking member, take out the house key, open the door, take the laundry then re-lock the house door, replace the house key and lock the whole collection device in place. Of course the householder can leave only the house key and no money, or can leave the laundry outside the house and not even place the receptacle on the plate.

2

For the return trip, the householder can leave the key to the house and the money in the receptacle and lock it. The laundry driver can unlock the receptacle, then leave the laundry inside the house door instead of outside and then relock the house door, replace the house key in the container with whatever change is necessary, with or without a receipt, together with the house key all outside the house in the container.

The householder can then unlock and remove the receptacle, leaving the base plate in position until the next trip of the laundryman. The householder opens the receptacle, takes out the change, and receipt if any, and the house key to be put back inside the door.

He can put the receptacle back and lock it outside, but preferably he stores it on a second holding plate fixed inside the house, locks it and leaves his key in the lock, all parts of the receptacle being together in one place.

If he has another receptacle with its keys for the milkman, he can put it on the same outside holding plate, or of course he can have more than one fixed outside plate for use by each service.

Preferably he should have one or more plates fixed inside the house to be conveniently marked or labeled and lock on the outside plate only one receptacle as a signal for the particular service to call.

In the drawings:

Fig. 1 is an elevation of my device in place on the frame of a building or door.

Fig. 2 is a sectional elevational view on a vertical plane 30 of the device shown in Fig. 1.

Fig. 2A is a sectional detail view of a locking prong passing through a locking prong hole and into a locking prong slot.

Fig. 3 is an elevational edge view of a holding plate 35 alone attached to such a frame.

Fig. 4 is an elevational face view from the right of Fig. 3.

Fig. 5 is a sectional view on line 5—5 of Fig. 1.

Fig. 6 is an elevational view of the tubular inside 40 member alone.

Fig. 7 is a view as from the left of Fig. 6.

Fig. 8 is an elevational view of an inside member somewhat different from the one shown in Fig. 6.

In the drawings, F represents a door frame to which 45 a base or holding plate P is attached by screws S, S, each having a head 10 and a shank 11, each of which passes through an attaching screw hole 13 in plate P.

Plate P preferably has a projecting center guide 40 in the form of a pin, and around its rim has a plurality of annularly disposed locking prong slots 42, and annularly disposed attaching lugs 41, each with a head 43 and shank 44.

E represents a tubular outer supporting member with a cylindrical wall 57 and an inside base 58, the base 58 having a center guide hole 50 to slip over guide pin 40 and at least one annularly disposed, key hole shaped attaching lug slots 51 each positioned to engage a lug 41. The head 43 of each lug 41 can pass through the enlarged aperture 53 of lug slots 51 but cannot pass through the reduced aperture 54 of the slots 51.

To attach outer member E to plate P, member E can be pushed on to plate P guided by hole 50 and pin 40 and then turned to allow lug heads 43 to pass through the enlarged apertures 53 of lug slots 51 and then again turned so that shanks 44 will pass into reduced apertures 54, thus holding member E detachably to plate P.

Member E is also provided around the rim of its base 58 with annularly disposed locking prong holes 52 and it should be noted that when in place on plate P, member E effectively covers the screws S to prevent removal of the plate.

Outer member E has an open end at outside rim 55

proximate which is a radially outwardly projecting hole locking rib 56.

Member E is a cap member and member G, to be described, is a cup member.

G represents a tubular inner locking member or cup having a tubular wall 67 of a size to telescope inside wall 57 of member E, an open end at inner rim 68 from which a plurality of locking prongs 62, 62, project axially. The prongs 62 are so positioned that when member G is pushed into member E, the prong 62 can be pushed through holes 52 into slots 42, the members G, E and P thereby being detachably held together and in place and the member E held against rotation on plate P.

Member G is also provided with a closed outside end 60 near which is an outwardly projecting stop rib 65 which stops member G when entering member E at a position where the locking bolt 66 of a lock L carried by end 60 can be turned by a key K to enter locking rib 56 of member E, Fig. 6.

The outer and inner tubular members E and G are thus locked to plate P as prongs 62 passing through holes 52, 52 and slots 42, 42 prevent the members E and G from being turned on plate P and bolt 66 entering rib 56 prevents member G from being pulled out of member E, and the heads 43 of lugs 41 prevent member E from being pulled away from plate P.

Lock L is shown as off center of end 60 of member G so that bolt 66 can be moved to enter rib 56 or to withdraw it by the use of a key K.

As shown in Fig. 6, lock bolt 66 of inner member G passes through lock bolt hole 64 in the cylindrical wall 67 of member G.

As shown in Fig. 8, the stop rib 65 can be omitted in an inner member M similar to G if the distance between its closed end 70, in which is lock 71, along its curved surface 77 to its lock bolt hole 74, is just enough to register with a lock bolt 76 of a lock 71 which is similar to lock L.

I claim:

1. A collection device for use outside a building having a frame; comprising a holding base plate for attaching to the frame, such plate having attaching screw holes, a projecting center guide, annularly disposed attaching lugs with heads, and annularly disposed peripheral slots for receiving prongs; a receptacle removably attached to the holding plate including a tubular outer supporting member having an inside base with a center guide hole for receiving said guide, annularly disposed key hole slots for receiving said headed lugs, annularly disposed holes for receiving said prongs and an outwardly projecting annular locking rib proximate its outside rim, and said receptacle including a tubular inner locking member positioned inside the outer supporting member said inner member having an inside rim with a plurality of axially extending locking prongs projecting therefrom and passing through the prong receiving holes in the inside base of the outer supporting member and into the prong receiving slots in the holding plate, a closed outside end, an outwardly projecting annular stop rib and a locking bolt slot proximate thereto, a key lock on said outside end having a lock bolt passing through the locking bolt slot into the locking rib; and attaching screws to attach the plate to the frame each with a shank to pass through an attaching screw hole.

2. A collection device for use outside a building having a frame; comprising a holding base plate having attaching means for attaching to the frame, such plate having attaching lugs with heads, and having at least one locking prong slot; a receptacle adapted to cover and conceal the attaching means of said plate and comprising a tubular outer supporting member having an inside base with attaching lug slots of key hole shape, at least one locking prong hole and an outwardly projecting annular locking rib proximate its outside rim, and a tubular inner locking member positioned inside the outer support-

ing member said inner member having an inside rim with at least one axially extending locking prong projecting therefrom and passing through the locking prong holes in the inside base of the outer supporting member and into the locking prong slots in the holding plate, a closed outside end, and a locking bolt slot proximate thereto and a key lock on said closed outside end having a lock bolt passing through the locking bolt slot into the locking rib.

3. A tamper resistant collection receptacle for household use comprising a circular base plate member having a plurality of screws spaced therearound at a uniform radius within the periphery thereof for permanently affixing the same substantially flatwise against a surface; a hollow cylindrical cap member equal in diameter to said base plate member and having an opening at one end and a closed bottom at the other end, said closed bottom being of an area to entirely cover the screws of said base plate when flatwise thereagainst; a plurality of axially extending, integral hooks spaced around said plate at the same radius as said screws and arcuate key hole slots formed in the bottom of said cap member in position to register with said hooks for attaching and detaching said cap member to said plate by relative rotation unidirectionally thereof for a short angular distance around the central longitudinal axis of said cap member, and lockable closure means for said tubular cap mounted to cover the end opening thereof when in closed position and to uncover said opening when moved outwardly relative to said cap member, said closure means having axially extending prongs axially slideable through prong holes in said cap member into prong slots in said plate member for locking said cap member against rotation on said plate member when the closure means is in closed position covering said opening.

4. A tamper resistant collection receptacle for household use comprising a base plate member having means for permanently affixing the same substantially flatwise against a surface; a hollow tubular cap member having an opening at one end and a closed bottom at the other end, said closed bottom being of an area to entirely cover the affixing means of said base plate when flatwise on said base plate, axially extending headed elements affixed to one of said members and arcuate key hole slots formed in the other of said members at a spaced radial distance from the centre points thereof for attaching and detaching said cap member to said plate by relative rotation, unidirectionally thereof for a short angular distance around the central longitudinal axis of the cap member, lockable closure means for said tubular cap mounted to cover the end opening thereof when in closed position and to uncover said opening when moved outwardly relative to said cap, said closure means having axially extending prongs axially slideable through prong holes in said cap member into prong slots in said plate for locking said cap against rotation on said plate when the closure means is in closed position covering said opening; an axially extending smooth faced guide pin on one member and an axially extending smooth faced guide pin hole on the other member, both the pin and the hole being along the longitudinal axis of said cap member for guiding the rotation thereof on said base plate member.
